(57) **CLAIM**

The ornamental design for a display screen portion with
graphical user interface, as shown and described.

DESCRIPTION

The present application is also related to U.S. Design patent
application Ser. No. 29/623,844, filed Oct. 27, 2017; U.S.
Design patent application Ser. No. 29/623,815, filed Oct. 27,
2017; U.S. Design patent application Ser. No. 29/679,663,
filed Feb. 8, 2019; U.S. Design patent application Ser. No.
29/623,820, filed Oct. 27, 2017, now U.S. Design Pat. No.
D847,858; U.S. Design patent application Ser. No. 29/680,
898, filed Feb. 21, 2019; U.S. Design patent application Ser.
No. 29/623,826, filed Oct. 27, 2017; and U.S. Design patent
application Ser. No. 29/623,833, filed Oct. 27, 2017, the
entire disclosures of which are incorporated herein by ref-
erence.

FIG. 1 is a front view of a display screen portion with
graphical user interface according to our design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The dot-dash broken line showing of the display screen
portion and all other broken line showing portions of the
graphical user interface are included for the purpose of
illustrating portions of the article that form no part of the
claimed design. In the figures, the perimeters of the portion
of the underlying display screen and the graphical interface
are understood to be flush.

(Continued)

The appearance of the image sequentially transitions between FIGS. 1-6. The process or period in which one image transitions to another image forms no part of the claimed design.
